United States Patent Office

Des. 210,954
Patented May 7, 1968

210,954

CHRISTMAS ORNAMENT OR THE LIKE

Dario Maranduzzo, Via Aretina 161,
Florence, Italy

Filed Sept. 22, 1966, Ser. No. 3,986

Term of patent 14 years

(Cl. D29—1)

FIG. 1 is a front perspective view of a Christmas ornament or the like showing my new design;

FIG. 2 is another front perspective view thereof as it appears with the cover removed; and

FIG. 3 is a rear perspective view of the cover portion thereof.

I claim:

The ornamental design for a Christmas ornament or the like, as shown.
